United States Patent Office

Des. 231,122
Patented Apr. 2, 1974

231,122

CASH REGISTER OR SIMILAR ARTICLE

James C. Kaufman, South Bend, Ind., and William L. King, Kettering, Ohio, assignors to The National Cash Register Company, Dayton, Ohio

Filed Mar. 6, 1973, Ser. No. 338,721

Term of patent 14 years

Int. Cl. D18—01; D14—02; D20—02
U.S. Cl. D52—4 A

FIG. 1

FIG. 2

FIG. 3

FIG. 4

FIG. 5

FIG. 6

FIG. 7

FIG. 8

FIG. 1 is a right front perspective view of a cash register or similar article showing our new design;
 FIG. 2 is a left rear perspective view thereof;
 FIG. 3 is a front elevational view;
 FIG. 4 is a rear elevational view;
 FIG. 5 is a right side elevational view;
 FIG. 6 is a left side elevational view;
 FIG. 7 is a right front perspective view of a modified form of our new design;
 FIG. 8 is a left rear perspective view thereof.

We claim:

The ornamental design for a cash register or similar article, as shown and described.
